FIG. 1

FIG. 2

FIG. 3

FIG. 4

FIG. 5

FIG. 6

FIG. 7

FIG. 8

FIG. 1 is a front view of the folding box, looking along a diagonal of the square bottom and facing an inclined panel which ends at the narrow transverse top. The rear not shown is the same as the front shown except for the presence at the rear of the top closure flap.

FIG. 2 is a view from the right of FIG. 1 at an angle of 45°, along the sides of the square bottom, so that the inclined panel which appears in the center of FIG. 1 is at the left in FIG. 2.

FIG. 3 is a view from the right of FIG. 1 at an angle of 90°, along the narrow top, so that the inclined panel which appears in the center of FIG. 1 is visible mainly from an edge.

FIGS. 4, 5, 6, and 7 are respectively a top plan view of FIG. 1, a section along the line 5, 5, a section along the line 6, 6, and a bottom plan view.

FIG. 8 is a perspective view showing the bottom and three of the six sides.

We claim:

The ornamental design for a folding box, as shown and described.
